(57) **CLAIM**

The ornamental design for a protective case for electronic tablet, as shown and described.

DESCRIPTION

FIG. 1 is a rear perspective view of a protective case for electronic tablet, showing our new design;
FIG. 2 is a front elevational view of the protective case for electronic tablet of FIG. 1;
FIG. 3 is a rear elevational view of the protective case for electronic tablet of FIG. 1;
FIG. 4 is a right side elevational view of the protective case for electronic tablet of FIG. 1;
FIG. 5 is a left side elevational view of the protective case for electronic tablet of FIG. 1;
FIG. 6 is a top plan view of the protective case for electronic tablet of FIG. 1;
FIG. 7 is a bottom plan view of the protective case for electronic tablet of FIG. 1;
FIG. 8 is a rear perspective view of the protective case for electronic tablet of FIG. 1, shown in an alternate, unfolded configuration of use;
FIG. 9 is a front elevational view of the protective case for electronic tablet of FIG. 8;
FIG. 10 is a rear elevational view of the protective case for electronic tablet of FIG. 8;
FIG. 11 is a left side elevational view of the protective case for electronic tablet of FIG. 8;
FIG. 12 is a right side elevational view of the protective case for electronic tablet of FIG. 8;
FIG. 13 is a top plan view of the protective case for electronic tablet of FIG. 8; and,
FIG. 14 is a bottom plan view of the protective case for electronic tablet of FIG. 8.
Dashed lines form no part of the claimed design.
